(57) **CLAIM**

The ornamental design for a tube case, substantially as shown and described.

DESCRIPTION

FIG. 1 is a perspective view of the tube case design (with four hardware items shown dashed since they do not form a part of the design, and in FIG. 2 also),
 FIG. 2 is a top plan view thereof,
 FIG. 3 is a bottom plan view thereof,
 FIG. 4 is a side view thereof,
 FIG. 5 is an opposite side view thereof,
 FIG. 6 is a front view thereof; and,
 FIG. 7 is a rear view.
